(57) CLAIM

The ornamental design for a beauty massage device with base in combination as shown and described.

DESCRIPTION

1. Beauty massage device with its base

1.1 : Perspective

1.2 : Front

1.3 : Back

1.4 : Top

1.5 : Bottom

1.6 : Left

1.7 : Right

1.8 : Perspective in use

1.9 : Alternate perspective in use, shown in a separated state
Reproduction 1.1 is a perspective view of a beauty massage device with base in combination showing our new design; Reproduction 1.2 is a front elevational view thereof; Reproduction 1.3 is a rear elevational view thereof; Reproduction 1.4 is a top plan view thereof; Reproduction 1.5 is a bottom plan view thereof; Reproduction 1.6 is a left side elevational view thereof; Reproduction 1.7 is a right side elevational view thereof; Reproduction 1.8 is a perspective in use view of the beauty massage device with base in combination; and Reproduction 1.9 is an alternate perspective in use view of the beauty massage device with base in combination, shown in a separated state.

The broken lines in the drawings show portions of the beauty massage device with base in combination that form no part of the claimed design.
